AUTHUR S. WHITE AND MARK A. WISEMAN, OF MUSKEGON, MICHIGAN, ASSIGNEES
TO WHITE AND HALLOCK, INC., OF MUSKEGON, MICHIGAN, A CORPORATION OF
MICHIGAN.

BEATER.

Application filed March 10, 1927. Serial No. 174,118.

The present invention relates to improvements in beaters adapted to be used for culinary purposes, such as whipping cream and eggs.

5 The primary object of the present invention is to provide a new and improved beater which is simple, sturdy and inexpensive in construction, and which is adapted to apply an extensive and effectual shearing force 10 on the liquid.

A more specific object resides in the provision of a frame which is formed out of a single piece of metal, which can be cheaply and quickly manufactured, and which has 15 baffle means and shearing edges for increasing the bearing action.

Further objects and advantages will become apparent as the description proceeds.

In the accompanying drawings, 20 Figure 1 is an elevational view of a beater constructed in accordance with our invention.

Fig. 2 is a vertical section taken along line 2—2 of Fig. 1.

25 Fig. 3 is a horizontal section taken along line 3—3 of Fig. 1.

While the invention is susceptible of various modifications and alternative constructions, we have shown in the drawings and 30 will herein describe in detail the preferred embodiment thereof, but it is to be understood that we do not thereby intend to limit the invention to the specific form disclosed, but intend to cover all modifications and 35 alternative constructions falling within the spirit and scope of the invention, as expressed in the appended claims.

Referring to the preferred embodiment of 40 our invention shown in the drawings, the beater comprises a vertical frame 10 which is formed out of a single bar of metal. The bar is bent to form a U-shaped bracket 11 having upper and lower parallel arms 12 and 13. Any suitable handle may be provided 45 for the frame. In the present instance the bar is bent above the arm 12 to form a handle 14 integral with the frame. From the arm 13, the bar is bent downwardly to form a side frame member 16. Preferably the member 16 is slightly inclined outwardly from 50 the arm 13 so as to provide strength and to prevent undue flexure of the frame by pressing downwardly on the handle 14. The lower end of the member 16 is slightly bent to

form a vertical baffle section 17. The lower 55 end of the bar is bent substantially at right angles to the section 17 to form a bottom member or bar 18. Preferably, the bottom member 18 is curved concave upwardly. The free end of the bottom member 18 is struck 60 up generally at right angles to form a baffle arm or plate 19 opposite the baffle section 17.

Rotatably mounted in the arm 13 and the bottom member or strip 18 is a vertical shaft 20. A pinion 21 is fixed on the upper end 65 of the shaft 20, and preferably is secured thereto by upsetting the metal on the end of the shaft, as shown at 22. The upper end of the shaft 20 is reduced in size by this offsetting of the metal, and is journaled in a hole 70 23 in the arm 13. To hold the shaft 20 in vertical position, its upper end is riveted. In mesh with the pinion 21 is a relatively large gear 24 which is journaled on a stud 25 on the bracket 11, and which is provided 75 with a suitable handle 26. Preferably, the stud 25 is riveted to the bracket 11. In the present instance, the gear 24 has a plurality of holes or slots 27 stamped therethrough next to its periphery and meshing with the 80 pinion 21.

A fan or propeller member 28 is rigidly fixed on the lower end of the shaft 20 directly over the bottom member 18 and between the baffle section 17 and the baffle arm 19, and is provided with a plurality of inclined blades, vanes or fins 29 inclined upwardly and forwardly with respect to the direction of rotation, so as to apply a downward thrust to the liquid. In the present instance, the propeller member is secured to the shaft 20 by off-setting the metal at the lower end of the latter, as indicated at 30. The reduced lower end of the shaft 20 fits into a hole 31 in the bottom strip 18, and is riveted to hold the shaft in vertical position. Preferably, the blades 29 are formed by twisting the metal between a plurality of alternately long and short radial slots 32 and 33 cut in from the periphery of the propeller member, and the propeller member is concave upward. The best results are obtained when the slots 32 and 33 are narrow and are formed with sharp edges instead of being rounded, and when the propeller member 28 and the bottom member 18 are positioned closely together.

The baffle arm 19, struck up from the

bottom strip 18, is inclined rearwardly with respect to the direction of rotation of the propeller member 28, and is twisted to present a surface laterally inclined outwardly and rearwardly to the swirling liquid.

In use, the bottom strip 18 rests on the bottom of the container for the liquid (not shown). The propeller member 28 has a sharp inherent shearing action. This action is increased by the tendency of the propeller member 28 to force the liquid into the confined space between it and the bottom of the container. The propeller member 28 also serves to direct the liquid against the baffle section 17, the bottom strip 18 and the baffle arm 19 which impede the swirling liquid. The inclined baffle surface of the arm 19 serves to shear the liquid, to raise the same by virtue of its area so as to aerate the liquid, and to direct the same toward the vortex. It will be evident that we have provided a beater that is simple, sturdy and inexpensive in construction, and that can be easily and quickly manufactured.

25 We claim as our invention:

1. A beater having, in combination, a frame member bent to comprise an upper bracket having spaced horizontal arms, a side member inclined from the lower arm and forming a baffle section at its lower end, a horizontal bottom strip underlying said lower arm and being concave upwardly, and a baffle arm struck up from the free end of said strip and opposite said baffle section, a shaft journalled in said lower arm and said bottom strip, a propeller mounted on said shaft over said bottom strip and between said baffle section and said baffle arm, and means on said bracket for rotating said propeller.

2. A beater having, in combination, a frame, a bottom strip formed integral with said frame, a baffle arm struck up from said bottom strip, a propeller member mounted for rotation directly over said strip and in closely spaced relation thereto, said baffle arm being inclined rearwardly with respect to the direction of rotation of said propeller member, and being twisted to form a rearwardly and outwardly inclined baffle surface, and means for rotating said propeller.

3. A beater having, in combination, a frame comprising an integral part bent to

form an upper support, a side member extending downwardly from said support, a horizontal bottom member extending laterally from the lower end of said side member and underlying said support, and a baffle arm struck up from the free end of said bottom member, a shaft journalled in said bottom member, a propeller mounted on said shaft over said bottom member, and means on said support for rotating said propeller.

4. A beater having, in combination, a frame member comprising a bar bent to form a central member, a depending side member inclined from said central member and forming a baffle section at its lower end, a horizontal bottom strip, and a baffle arm struck up from the free end of said strip and opposite said baffle section, a shaft journalled in said central member and said bottom strip, a propeller mounted on said shaft over said bottom strip and between said baffle section and said baffle arm, and means for rotating said propeller.

5. A beater having, in combination, a stationary frame, a curved bottom strip formed integral with said frame and being concave upward, a shaft rotatable in said frame, a propeller member fixed on said shaft, baffle means extending up from said bottom strip, and means for rotating said shaft.

6. A beater having, in combination, a frame, a bottom strip formed integral with said frame and having a free end, a shaft rotatable in said frame, a propeller member fixed on said shaft and having vanes inclined upwardly and forwardly to force liquid downwardly against said bottom strip, a baffle arm extending up from the free end of said bottom strip, and means for rotating said shaft.

7. A beater having, in combination, a frame, a bottom strip on said frame, a shaft rotatable in said frame, a propeller member fixed on said shaft, baffle means extending up from said bottom strip, said baffle means being inclined from the vertical, and means for rotating said shaft.

In testimony whereof we have hereunto affixed our signatures.

ARTHUR S. WHITE.
